(57) **CLAIM**

The ornamental design for an outsole for a shoe, as shown and described.

DESCRIPTION

FIG. 1 is a bottom, perspective view of an outsole for a shoe showing an embodiment of our new design;

FIG. 2 is a bottom view of the outsole for a shoe of FIG. 1;

FIG. 3 is a top view of the outsole for a shoe of FIG. 1;

FIG. 4 is a front view of the outsole for a shoe of FIG. 1;

FIG. 5 is a rear view of the outsole for a shoe of FIG. 1;

FIG. 6 is a right side view of the outsole for a shoe of FIG. 1;

FIG. 7 is a left side view of the outsole for a shoe of FIG. 1;

FIG. 8 is an enlarged perspective view of the area of the outsole for a shoe labeled “8” in FIG. 1;

FIG. 9 is a bottom, perspective view the outsole for a shoe of FIG. 1 shown with additional environmental subject matter;

FIG. 10 is a bottom view of the outsole for a shoe of FIG. 9;

FIG. 11 is a top view of the outsole for a shoe of FIG. 9;

FIG. 12 is a front view of the outsole for a shoe of FIG. 9;

FIG. 13 is a rear view of the outsole for a shoe of FIG. 9;

FIG. 14 is a right side view of the outsole for a shoe of FIG. 9; and,

FIG. 15 is a left side view of the outsole for a shoe of FIG. 9.

The broken lines depict unclaimed subject matter and form no part of the claimed designs. The long dash-short dash broken lines indicate the unclaimed boundaries of the claimed designs.

The embodiments of an outsole for a shoe described in FIGS. 1–15 depict an outsole for a right-foot shoe. Further embodiments of the claimed design include an outsole for a left-foot shoe, views of which are mirror images of the views of the right-foot shoe in FIGS. 1–15.
